United States Patent Office.

RAPHAEL MORITZ SELDIS, OF NEW YORK, N. Y.

Letters Patent No. 104,780, dated June 28, 1870.

IMPROVEMENT IN MUFFS.

The Schedule referred to in these Letters Patent and making part of the same.

To all whom it may concern:

Be it known that I, RAPHAEL MORITZ SELDIS, of the city, county, and State of New York, have invented a new and improved Muff; and I do hereby declare that the following is a full, clear, and exact description thereof, which will enable others skilled in the art to make and use the same, reference being had to the accompanying drawing forming part of this specification.

Figure 1 represents a perspective view of my improved muff.

Figure 2 is a transverse section of the same.

Similar letters of reference indicate corresponding parts.

This invention relates to a new manner of securing pocket flaps on muffs, with a view of economizing material and labor in their manufacture. The pocket flaps were heretofore separately secured to the covering of the muff, and a corresponding opening had to be left in said covering before applying it.

My invention consists in cutting the flap out of the muff-covering after the same has been secured around the muff, and without detaching the said flap from the cover. The saving, in labor especially, by this proceeding is considerable.

A, in the drawing, represents the body of a muff, of suitable kind, size, and form. The same is covered with fur or other suitable material.

It has on one or more sides a pocket, *a*, which is closed and concealed by a flap, *B*. This flap may be of triangular or other suitable shape. It is produced by cutting through the fur covering, either before or after the same has been applied to the muff, and forming thereby the flap without detaching it from the covering. The upper part, where the flap is not separated from the covering, constitutes the hinge on which the flap is turned to open or close the pocket.

Heretofore these flaps were sewed to the muff and made the same thereby the more expensive.

Having thus described my invention,

I claim as new and desire to secure by Letters Patent—

The muff provided with a pocket-flap, *B*, which is formed by incisions through the covering of the muff, as set forth.

RAPHAEL M. SELDIS.
